Patented Oct. 9, 1923.

UNITED STATES PATENT OFFICE.

SYLVIE MONTEGUT, OF PARIS, FRANCE.

DESIGN FOR A CARTON.

Application filed April 26, 1923. Serial No. 5,963. Term of patent 3½ years.

To all whom it may concern:

Be it known that I, SYLVIE MONTEGUT, a citizen of France, and a resident of Paris, Department of Seine-et-Oise, France, have invented a new, original, and ornamental Design for Cartons, of which the following is a specification, reference being had to the accompanying drawing, forming a part thereof.

The figure represents a carton embodying my new design.

I claim:

The ornamental design for a carton, as shown.

SYLVIE MONTEGUT.

Witnesses:

W. R. SCOTT,
CHARLES D. WESTCOTT.
